F. KEMPTER

MACHINE FOR WASHING RUBBER AND THE LIKE

Filed Nov. 12, 1923

Inventor:

Fritz Kempster
by *Sinclair* Attorney

UNITED STATES PATENT OFFICE.

FRITZ KEMPTER, OF STUTTGART, GERMANY.

MACHINE FOR WASHING RUBBER AND THE LIKE.

Application filed November 12, 1923. Serial No. 674,409.

To all whom it may concern:

Be it known that I, FRITZ KEMPTER, a citizen of Germany, residing at Stuttgart, Germany, have invented certain new and useful 5 Improvements in Machines for Washing Rubber and the like, of which the following is a specification.

My invention refers to improvements in devices for washing rubber and the like in 10 which rotary squeezing rolls are disposed in a washing trough, the bottom of which is slotted after the manner of a sieve, removable closing ledges being introduced into these slots.

15 In machines of this kind, these removable ledges are not easily accessible. In order to replace them, it is necessary to insert the hand into the channel below the trough, and the removal of the ledges is particularly difficult in the case where foreign bodies or 20 small pieces of rubber have been caught between the bottom and the ledges. Moreover, each ledge forms an obstacle with regard to the other ledges which extend across the entire width of the trough and are comparatively thin, whereby they are liable to get 25 easily bent.

In the machine according to the present invention, these drawbacks are avoided by 30 arranging the slotted bottom together with the closing ledges in an inclined plane. I am thus enabled to provide a lateral opening which can be closed by a cover and through which each ledge can easily be removed. 35 Moreover, the different parts serving to separate the foreign matter from the rubber can now be arranged on one side near the lowest point of the bottom, the machine being thus rendered far simpler and smaller.

40 In the drawings affixed to this specification and forming part thereof, a device embodying my invention is illustrated diagrammatically in vertical section.

Referring to the drawing, *a* is the machine bed and *b* is the washing trough tiltably mounted on the bed. *f* and *g* are the squeezing rolls arranged in the trough for rotation in the direction of the arrows. The bottom of the trough is shaped in accordance 45 with the rolls and in the middle between the rolls the well known saddle piece *i* is arranged.

Several slots 8 extending across the whole width of the trough are provided in the bottom and closing ledges 4 are arranged to be 55 introduced into these slots from below, their ends being then inserted in suitable notches provided in the end faces of the trough.

The bottom is inclined as shown in the drawing and, consequently, the slots 8, as 60 well as the closing ledges 4 are disposed on different levels. This applies also to the rolls *f* and *g*.

The slots and closing ledges can easily be 65 inspected and the ledges removed through the channel 9 which can be closed by means of a hinged cover 10.

The protective edge *k* and the perforate 70 wall *m*, the settling chamber 11 and the overflow *v* are disposed on the opposite side. This arrangement provides for a higher and therefore larger sieve surface. On the other hand, such specifically heavy impurities as are carried by the upper roll *g*, are vigorously crowded together under the action of 75 the water current in the direction towards the protective edge *k* which forms the lowest point of the washing trough proper, whereby they are quickly removed out of reach of the rolls.

I wish it to be understood that I do not desire to be limited to the exact details of construction shown and described, for obvious modifications will occur to a person skilled in the art.

I claim:—

1. Device for washing rubber and the like, comprising in combination, a machine bed, a washing trough tiltably mounted on said bed, a pair of squeezing rolls mounted in 90 said trough in parallel with each other, an inclined slotted bottom underneath said rolls, closing ledges removably disposed in the slots of said bottom and a lateral opening in said trough through which these 95 ledges can easily be removed.

2. Device for washing rubber and the like, comprising in combination, a machine bed, a washing trough tiltably mounted on said bed, a pair of squeezing rolls mounted in said trough at different levels in parallel 100 with each other, an inclined slotted bottom underneath said rolls, closing ledges removably disposed in the slots of said bottom and

a lateral opening in said trough through which these ledges can easily be removed.

3. Device for washing rubber and the like, comprising in combination, a machine bed, a washing trough tiltably mounted on said bed, a pair of squeezing rolls mounted in said trough at different levels in parallel with each other, an inclined slotted bottom

underneath said rolls, closing ledges removably disposed in the slots of said bottom, a lateral opening in said trough through which these ledges can easily be removed, a sieve and a protective edge, being disposed on one side of said trough near the lower roll.

In testimony whereof I affix my signature.

FRITZ KEMPTER.
